UNITED STATES PATENT OFFICE.

HENRY WILLIAM SCHEILER, OF LINCOLN, ILLINOIS, ASSIGNOR OF ONE-HALF TO
STEPHEN A. FOLEY, OF LINCOLN, ILLINOIS.

WASHBOILER.

1,228,972.

Specification of Letters Patent.

Patented June 5, 1917.

Application filed February 15, 1916. Serial No. 78,488.

To all whom it may concern:

Be it known that I, HENRY W. SCHEILER, a citizen of the United States, residing at Lincoln, in the county of Logan and State of Illinois, have invented certain new and useful Improvements in Washboilers, of which the following is a specification.

This invention relates to boilers and has for its principal object the provision of means to support clothes or other articles within the boiler or within a container positioned in said boiler.

Another object of the invention resides in the provision of adjustable supporting means of the character stated in combination with a perforated container suspended in a boiler and spaced from the walls of the same, so that scorching of the articles within the container will be prevented.

20 The invention further resides in the provision of supporting and agitating means of the above-stated character which may be used with or without the container as desired.

25 A further object of the invention is to provide a boiler of this character which is extremely simple in construction, cheap and easy to manufacture and which is thoroughly reliable and efficient in operation.

30 With the foregoing and other objects in view, the invention consists in the novel features of construction, combination and arrangement of parts, as will be hereinafter more fully described, illustrated in the accompanying drawings and claimed.

In the drawings:

Figure 1 is a top plan of a boiler constructed in accordance with the invention;

Fig. 2 is a transverse section on line 2—2 of Fig. 1 looking in the direction indicated by the arrow;

Fig. 3 is a plan view of the means for holding the articles within the boiler;

Fig. 4 is a perspective of one of the supporting brackets.

Referring to the drawings by numerals, wherein is illustrated the preferred embodiment of my invention, 1 designates a boiler which is of the usual construction, being formed from any desired material into any convenient shape and having a bead 2 formed upon its upper edge.

A container 3 formed from any suitable material and of a size slightly less than the size of the boiler 1 is adapted to be arranged

within the boiler with its side and bottom walls in spaced relation to the side and bottom walls of the boiler. This container is perforated throughout the extent of its side and bottom walls so that the water within the boiler may readily pass thereinto. 60

The container 3 is open at its top and is preferably provided with an inwardly extending bead 4, the said bead being arranged outwardly with respect to the side wall of the container by off-setting the upper portion of the container, as at 5. This construction readily permits of the application of a perforated cover 6 to the container, the cover being provided with a flange adapted to rest upon the shoulder formed by laterally extending the container at 5. 65

The supporting means for the container 3 comprises any desired number of similarly constructed brackets 7. Each of these brackets preferably comprises a flat strip of material suitably curled at its ends, as at 8, for engagement with the beads 2 and 4 of the boiler 1 and container 3 respectively, a laterally extending arm 9 being provided upon the strip 7 and having a vertically extending portion 10 thereon for engagement with the inner wall of the boiler to hold the bracket, and thus the container, rigidly within the boiler. As before stated any desired number of these brackets may be provided for supporting the container within the boiler. However, but two of these brackets have been illustrated in the drawings and such number has been found sufficient to properly support the container. It may also be stated, that, if desired, any other suitable supporting means may be employed in place of the brackets shown. 70 80 85 90

The clothes or other articles to be boiled are placed within the container and the lid then applied thereto, the clothes being placed within the container while the same is either arranged within the boiler or removed therefrom, as is most convenient. 95 This construction serves to prevent steam pockets being formed in the clothes and prevents their raising within the boiler and thereby prevents the contents of the boiler from escaping over its edges. By arranging the container in spaced relation from the walls of the boiler scorching of the clothes therein is effectually prevented. A bar 11 has its ends curled as at 12 for engagement with the bead 2 of the boiler to hold the 100 105 110

same upon the boiler. This bar is adapted to be arranged transversely of the boiler intermediate its ends and is provided, centrally thereof, with a transversely extending 5 elongated opening 13.

A rod 14 is provided which is of a size in transverse section to be snugly received by the opening 13. This rod is provided at its upper end with a handle 15 and at its lower 10 end with oppositely extending arms 16, the arms being preferably four in number and extending from diametrically opposite points upon the rod, as is illustrated most clearly in Fig. 3 of the drawings. Two of 15 these arms are oppositely disposed and are relatively longer than the other two arms, the arms being so arranged in view of the elongated nature of the boiler. The rod 14 is provided throughout a portion of its 20 length with spaced recesses 17 which are formed in the opposite edges of the rod in pairs and in alinement. By this construction the rod may be moved vertically with respect to the bar 11 and then twisted 25 after the recesses have been alined with the bar to retain the arms 16 in any vertically adjusted position relative to the bar 11. The four arms 16 and 17 are loosely mounted upon the rod 14 between suitable spacing 30 collars 16'. This provides means whereby any desired number or quantity of clothes may be held within the boiler. The bar 11 and arms 16 together with their adjusting means may be used in conjunction with or 35 independently of the container 3, as will be understood. When the arms 16 together with their supporting and adjusting means are used in conjunction with the container 3 the rod 14 may be passed through a circular 40 opening in the cover 6 which will permit of rotation of the bar relative thereto during its adjustment.

From the foregoing description, taken in

connection with the accompanying drawings it is thought that the construction and operation of the improved boiler will be thoroughly understood and while I have herein shown and described one specific embodiment of my invention I do not wish to be limited thereto except for such limitations as the claims may impart. 45 50

I claim:

1. The combination with a boiler, of a bar supported upon the same, an article container suspended in said boiler, a rod extended through said bar and adapted to be adjusted vertically therein, a plurality of arms arranged in pairs crossing one another and loosely mounted upon the end of said rod, said arms being connected with one another, and a handle formed upon the upper end of said rod. 55 60

2. The combination with a receptacle, and a second receptacle supported therein and having a removable cover therefor which is provided with a central opening, a bar extending transversely across the first named receptacle and having a slot therein, a supporting rod extending through the openings in the bar and cover, and within the second 65 70 mentioned receptacle having notches in its longitudinal edges thereof, and members carried by the bar adapted to be engaged with the contents of the last mentioned receptacle, the supporting rod being adapted 75 to be arranged at right angles to the longitudinal center of the slot in the bar whereby certain of the notches in the supporting rod will be engaged with the walls of the slot. 80

In testimony whereof I affix my signature in presence of two witnesses.

HENRY WILLIAM SCHEILER.
